UNITED STATES PATENT OFFICE.

LEONARD L. WICKLAND, OF MINNEAPOLIS, MINNESOTA.

EYESHADE.

Application filed July 25, 1928. Serial No. 295,209.

This invention relates to new and useful improvements in eye shades, and an object of the invention is to provide an eye shade constructed of a single piece of sheet material.

A further object of the invention is to provide an eye shade having a crown band integrally formed with the upper inner edge thereof and provided with a nose-piece, and 10 each end of the crown band having an extension integrally formed therewith, each adapted to be folded upon itself and formed to provide ear-engaging members cooperating with the nose-piece to support the eye shade upon the wearer's head.

The particular object of the invention, therefore, is to provide an improved eye shade of simple and inexpensive construction, formed of a single piece of material, 20 and comprising ear-engaging members and a nose-piece, the latter being formed to support the shade in a position wherein the shade will not engage the wearer's forehead and temples.

25 Other objects of the invention will appear from the following description and accompanying drawings and will be pointed out in the annexed claims.

In the accompanying drawings, there has 30 been disclosed a structure designed to carry out the various objects of the invention, but it is to be understood that the invention is not confined to the exact features shown as various changes may be made within the 35 scope of the claims which follow.

In the accompanying drawings forming part of this specification:

Figure 1 is a perspective view illustrating the improved eye shade in position upon 40 the wearer's head;

Figure 2 is a vertical sectional view on the line 2—2 of Figure 3;

Figure 3 is a plan view of Figure 2;

Figure 4 is a view, showing the outline 45 of the complete eye shade as developed from a single piece of material;

Figure 5 is a detail sectional view on the line 5—5 of Figure 2, showing the preferred manner of forming the ear-engaging members;

Figure 6 is a view showing a modified form of ear-engaging members;

Figure 7 is a view showing another modification wherein the ear-engaging members 55 are adjustably connected with the crown band;

Figure 8 is an enlarged detail sectional view on the line 8—8 of Figure 7; and

Figure 9 is a view, showing the ear-engaging member illustrated in Figure 7, removed 60 from the crown band.

The novel eye shade featured in this invention comprises a body portion 2, preferably shaped like a crescent and having a crown band 3 integrally formed with the 65 upper inner edge thereof, as shown in Figures 1 and 3. A strap like member 4 is integrally formed with the crown band 3, intermediate of its ends as shown in Figure 4, and is adapted to be folded upon itself, 70 as shown in Figures 1 and 2, to provide a nose-piece 5, adapted to engage the bridge of the wearer's nose. (See Figures 1 and 2.)

The crown band 3 and nose-piece 5 are so formed that when the eye shade is positioned upon the wearer's head, as shown in Figures 1 and 2, the band 3 will be spaced from the wearer's forehead and temples to provide a space 6 therebetween. I have found it desirable to space the eye shade 75 from the wearer's forehead and temples because when thus supported upon the head, the eye shade will not tend to obstruct blood circulation, which often results when using eye shades of ordinary construction, which 80 are usually fitted closely against the forehead and temples. A shade spaced from the head as above described, is also more comfortable in hot weather as it permits free 85 circulation of air between the shade and 90 head.

Ear-engaging members or hooks 7 are integrally formed with the crown band 3, as best shown in Figure 4. These ear-engaging members are formed by providing an 95 integral extension 8 at each end of the crown band, having an off-set portion 9 adapted to be folded against the extension 8 along the dotted line 11, indicated in Figure 4. Figure 5 illustrates a cross-section of the hook 100 7, formed by folding the off-set portion 9 upon the extension 8, as above described. The ear-engaging members may be formed as shown in Figure 2, or, as shown in Figure 6, by means of suitable dies, after the 105 material has been folded upon itself as shown in Figure 5.

Figure 7 illustrates a modified form wherein ear-engaging members 12 are adjustably secured to the crown band 3. To 110 thus adjustably secure the members 12 to the crown band, the latter is provided with

a series of apertures 13, and similar apertures 14 are provided in the member 12, as shown in Figure 9. Suitable fastening means, such as split rivets 15, may then be inserted through the apertures 13 and 14 to secure the members 12 to the crown band, as shown in Figure 8. I have shown two groups of apertures 13 and 14 so as to securely hold the members 12 in position, but, if desired, one group of apertures might be used, in which case, it might be necessary to provide additional means to prevent the members 12 from oscillating about the axes of the rivets 15.

15 The novel eye shade featured in this invention is constructed of a single piece of sheet material, such for example, as paper or celluloid, and is first blanked to the form shown in Figure 4, by suitable dies not shown. The material 8 is then folded along the dotted lines 11 and the material is further bent along the dotted curved line 16 to the form shown in Figure 2, thereby providing the crown band 3. The extensions 8 and off-set portions 9, after being folded to the position shown in Figure 5, may then be bent to the form shown in either Figures 2 or 6, as may be desired. This may be accomplished by suitable dies.

30 The strap member 4, shown in Figure 4 is also folded upon itself as indicated in Figures 1 and 2, and the terminal 17 thereof suitably secured to the under side of the body 2 of the eye shade, preferably by a suitable adhesive. By thus securing the end portion 17 of the strap 4 of the nose-piece to the body 2, the crown band 3 and body 2 will be securely held in position, and will also be strengthened, as will readily be understood by reference to Figure 2. Also by forming the eye shade of a single piece of sheet material, it will readily be understood that the shade may be manufactured at a very low cost, thereby producing such an article which may be sold to the public at a nominal price. The device is also very light in weight and may be used, if desired, as an advertising specialty, the body portion 2 of the shade providing ample room for advertising matter and the like.

I claim as my invention:

1. An eye-shade constructed of a single piece of sheet material and comprising a body portion, a crown band integrally formed therewith, a nose-piece integrally formed with said band and comprising a strap-like portion folded upon itself and

having its end secured to said body portion, an extension integrally formed with each end of the crown band and shaped to provide ear-engaging members, said nose-piece and ear-engaging members cooperating to support the shade in position on the wearer's head with the crown band spaced from the forehead and temples.

2. An eye-shade constructed of a single piece of sheet material and comprising a body portion, a crown band integrally formed therewith, a nose-piece integrally formed with said band and comprising a strap-like portion folded upon itself and having its end secured to said body portion on the inner side thereof, an extension integrally formed with each end of the crown band and each having an offset portion adapted to be folded upon its respective extension to provide U-shaped ear-engaging members, said nose-piece and ear-engaging members cooperating to support the shade in position on the wearer's head with the crown band spaced from the forehead and temples.

3. A device of the class described, comprising a shade having a portion bent downwardly to provide a crown band having means for retaining the device on the wearer's head, and a nose piece integrally formed with said band and adapted to space the crown band from the head.

4. A device of the class described, comprising a shade formed of sheet material and having a portion bent downwardly to provide a crown band, means on said band for retaining the device on the wearer's head, and a nose piece formed with said crown band and having a portion engaging said shade whereby the latter is strengthened, said nose piece being shaped to space the crown band from the head.

5. A device of the class described, comprising a shade formed of sheet material and having a portion bent downwardly to provide an integral crown band having means for retaining the device on the wearer's head, and a strap-like member provided on said crown band and shaped to provide a nose piece, adapted to space the band from the head, said strap-like member having one end attached to the shade, whereby said band and shade are strengthened.

In witness whereof, I have hereunto set my hand this 20th day of July, 1928.

LEONARD L. WICKLAND.
